[57] CLAIM

The ornamental design for a chair, as shown and described.

DESCRIPTION

FIG. 1 is a prospective view from the front and the left side of the chair;

FIG. 2 is a left side elevational view of the chair of FIG. 1. The right side of the chair is substantially a mirror image of the left side, the difference being the omission of the two adjustment handles;

FIG. 3 is a front elevational view of the chair of FIG. 1;
FIG. 4 is a rear elevational view of the chair of FIG. 1;
FIG. 5 is a top plan view of the chair of FIG. 1; and,
FIG. 6 is a bottom plan view of the chair of FIG. 1.
